UNITED STATES PATENT OFFICE.

ARTHUR W. WADSWORTH AND ARTHUR P. CONANT, OF FORT THOMAS, KENTUCKY,
ASSIGNORS TO THE WADSWORTH WATCH CASE COMPANY, OF DAYTON, KEN-
TUCKY, A CORPORATION OF KENTUCKY.

DESIGN FOR A WATCHCASE APPENDAGE.

Application filed November 21, 1924. Serial No. 11,434. Term of patent 14 years.

To all whom it may concern:

Be it known that we, ARTHUR W. WADSWORTH and ARTHUR P. CONANT, citizens of the United States, residing at Fort Thomas, in the county of Campbell and State of Kentucky, have invented a new, original, and ornamental Design for Watchcase Appendages, of which the following is a specification, reference being had to the accompanying drawing, forming part thereof.

Figs. 1 and 2 are side and edge views of the watchcase appendage embodying our design, its relation to the watchcase and other appendages being indicated by a conventional showing thereof by dotted lines.

We claim:

The ornamental design for a watchcase appendage, substantially as shown.

ARTHUR W. WADSWORTH.
ARTHUR P. CONANT.
